KNITTING NEEDLE

Otto Lobl, Middleboro, Mass., assignor to Hero Mfg. Co., Inc., Middleboro, Mass., a corporation of Massachusetts

Application March 29, 1949, Serial No. 84,095

1 Claim. (Cl. 66—117)

1

This invention relates to improvements in knitting needles and the like. More especially it relates to reinforced plastic knitting needles and particularly to an improved reinforced pointed end region of such needles.

Plastic knitting needles have been available heretofore in the form of a plastic tube axially reinforced by a rod of metal which not only strengthens the needle but provides a desired resilient liveliness which is not characteristic of knitting needles which have been of plastic material throughout their cross-sections. Also, there are commercial and manufacturing advantages in using plastic materials in tubular form, in that continuous lengths of the tubing may be economically cut to approximate needle lengths, and the tubes are not required to be stiff but may be wound on reels or drums from which the material may be withdrawn as needed. The metal rod axial reinforcement which is introduced into each cut length of tubing gives it needed stiffness coupled with the mentioned resilient liveliness.

Heretofore, however, the pointed ends of such reinforced plastic needles have been too weak to withstand the stresses put upon them in use. The tapering pointed ends frequently break off or become bent, in service. This has been due to the prior practice of drawing and shaping the plastic at the tapering point region to provide a solid mass of plastic extending outward from the end of the metal reinforcing rod, and this tapering point, although solid of the plastic material, yields under pressure and bends or breaks at the region of abrupt termination of the reinforcement.

It is among the objects of the invention to provide a plastic knitting needle, or the like, having a metallic axial reinforcing element extending a substantial distance within a tapering pointed end portion of the needle as well as within the body extent thereof.

Another object is to provide a knitting needle, or the like, having a tube of plastic material within which extends a metallic reinforcing rod, one end portion of the rod having substantial tapering extent, and one end portion of the plastic tube being formed with exterior tapering extent to the point of the needle with the said tapering end portion of the rod extending within and reinforcing the said formed tapering end portion of the plastic tube.

A further object is to provide a knitting needle, or the like, comprising a plastic tube and a metallic rod extending axially within the tube, the rod

having an end portion of substantial extent having gradually increasing diameter inward from its extreme end, said tube being molded around the said end portion of the rod with gradual tapering extent to the end of the needle.

It is, moreover, my purpose and object generally to improve the structure and durability of plastic knitting needles and especially the tapering end portions of such needles.

10 In the accompanying drawing:

Fig. 1 is an elevational view of a knitting needle embodying features of the invention;

Fig. 2 is a medial longitudinal cross-sectional view of a plastic tube from which the outer surface portion of the needle of Fig. 1 may be formed;

Fig. 3 is an elevational view of a metal reinforcing rod for the tube of Fig. 2;

Fig. 4 illustrates the combining of the tube and rod of Figs. 2 and 3, respectively, with a terminal head secured at one end of the tube; and

Fig. 5 illustrates the tube and rod combined as in Fig. 4 but with the plastic tube formed over the tapering end portion of the rod to provide a reinforced tapering pointed end for the completed needle.

Referring to the drawing, my improved needle comprises a metallic core rod 10 which preferably will be of steel but which may be of any other suitably stiff and resilient metal, such as brass or aluminum. According to the invention, one end portion of rod 10 gradually tapers to provide the pointed end 12.

Mounted on rod 10 is a body of material 16 having the nature that it provides a hard and durable surface but is moldable under heat and pressure. The material 16 may be of any of various available thermo-plastic materials of which nylon and vinyl resin products are examples. If desired, the material 16 may be molded around the core rod 10 but, in a preferred form, the material 16 will be tubes of plastic material of indefinite length from which lengths approximating needle lengths may be cut as needed. Nylon tubes and tubes made of various available synthetic resins, such as available vinyl resin products, for example, provide the needed hard and durable surfaces with a suitable amount of stiffness, yet long lengths of the tubing conveniently may be wound on drums or reels to facilitate handling and storage, and the tubing may be withdrawn and cut as needed.

The axial hole 18 through the tubing will be of diameter to nicely receive therein one of the rods 10, with an end portion of a cut length of

tubing projecting a little beyond the tapered end portion 12 of the rod, as at 20 in Fig. 4, when the other ends of the rod and tube are in register in a common plane. A metallic head cap 22 is secured over the registering ends of the rod and tube as by indenting portions of the cap walls into the tube material as at 24.

After the head cap 22 has been secured in place, with its end wall constituting an abutment for the adjacent end of rod 10, the opposite end portion of the tube is softened by heat and molded under heat and pressure around the tapering part 12 to provide a smoothly tapering end portion 26 on the needle as shown in Figs. 1 and 5, so that the main extent of this tapering point portion of the molded plastic material is axially reinforced by the tapering portion 12 of rod 10.

The invention effectively overcomes the prior problem of bending and breaking off of the pointed end portions of reinforced plastic knitting needles as heretofore constructed, and my improved needles have a superior degree of resilient liveliness as compared with all prior comparable needles of which I am aware.

I claim as my invention:

A knitting needle comprising a metallic core element, a tube of moldable material on the core element with one end of the tube in register with

an end of the core element, an end cap mounted over said registering ends of the tube and element and secured to the tube with a wall of the end cap constituting an abutment limiting axial movement of the core element in one direction, said core element, at its opposite end, having a portion of substantial extent gradually tapering with its smaller diameter at said opposite end, said tube being molded to gradually tapering form around said tapering end portion of the core element, with said abutment wall of the end cap preventing relative movement of the rod and tube during application of the molding pressure.
